(57) **CLAIM**

The ornamental design for an antenna element, as shown and described.

DESCRIPTION

FIG. 1 is a perspective view of the top, front and right side of an antenna element showing our new design;

FIG. 2 is a perspective view of the bottom, rear and left side thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The elements shown in broken lines are for illustrative purposes only and form no part of the claimed design.
